Application July 1, 1936, Serial No. 88,299
In Germany July 10, 1935

19 Claims. (Cl. 62—5)

Our invention relates to refrigeration, and more particularly to a control device for refrigeration apparatus.

It is an object of our invention to provide an improved control device for modifying the operation of refrigeration apparatus to initiate defrosting thereof, the device being operative to terminate the defrosting automatically.

Further objects and advantages of our invention will become apparent from the following description and accompanying drawings forming a part of this specification and of which Fig. 1 diagrammatically illustrates refrigeration apparatus provided with a control device embodying our invention; Fig. 2 is a sectional view taken at line 2—2 of Fig. 1 illustrating the control device more clearly; Fig. 3 is an enlarged fragmentary sectional view of parts of the control device shown in Fig. 2; Fig. 4 is a sectional view taken at line 4—4 of Fig. 3; and Fig. 5 is a sectional view taken at line 5—5 of Fig. 4.

Referring to Fig. 1, we have shown our invention in connection with a refrigerator cabinet 10 having thermally insulated walls 11 defining a storage compartment 12 into which access may be had by a door 13 hinged to the front of the cabinet. Within the storage compartment 12 is arranged a cooling element 14 of refrigeration apparatus for maintaining the storage compartment at a desired low temperature.

In the present embodiment we have shown the invention in connection with refrigeration apparatus of a uniform pressure absorption type containing an auxiliary pressure equalizing gas. The refrigeration apparatus comprises a generator 15 having a rear chamber 16 and a forward chamber 17 communicating with an upward extending stand-pipe or separator 18. The generator contains a body of absorption liquid having a suitable refrigerant in solution therein, and, although we do not wish to be limited thereto, the absorption liquid and refrigerant may be water and ammonia, respectively.

The generator 15 may be heated in any suitable manner, as by a gas burner 19, which projects its flame into the forward end of a horizontal flue 20 which extends through the generator. A suitable combustible gas is delivered from a source of supply through conduit 21, control valves 22 and 23 connected in series relation, and conduit 24 to the burner 19. A by-pass conduit 25 is provided around the valves 22 and 23 to maintain a pilot flame at the burner when either one of the valves 22 or 23 shuts off the main supply of gas to the burner.

The heat applied to the generator causes ammonia vapor and absorption liquid in chamber 16 to pass through an opening 25' in the lower end of a small vertical conduit 26 which constitutes a vapor lift and conducts ammonia vapor and absorption liquid to the upper part of the stand-pipe 18. The liberated ammonia vapor entering the stand-pipe 18 from conduit 26, as well as the ammonia vapor expelled from solution in the stand-pipe 18 and chamber 17, flows upward through an air-cooled rectifier 27 which condenses water vapor accompanying the ammonia vapor. The water condensed in the rectifier drains back to the generator, and the ammonia vapor flows upward to an air-cooled condenser 28 comprising a coil provided with a plurality of heat dissipating elements or cooling fins 29. The ammonia is liquefied in the condenser 28 by surrounding cooler air which flows over the surfaces of the coil and fins, and the liquefied ammonia flows through a conduit 30 into the upper section of an evaporator coil 14. The conduit 30 is U-shaped at its lower end to provide a liquid seal for preventing gas from entering the condenser 28.

An inert gas, such as hydrogen, enters the lower section of the evaporator coil or cooling element 14 from conduit 31 in counter-flow to the liquid ammonia. The ammonia evaporates and diffuses into the hydrogen with consequent absorption of heat from the surroundings of the evaporator. The lower section of the evaporator coil may be arranged within a shell 32 adapted to receive trays for freezing water since the ammonia evaporates at a lower temperature in this section of the evaporator coil. The upper section of the evaporator coil may be utilized for cooling the storage compartment since ammonia evaporates at a higher temperature in this section of the evaporator coil, a plurality of fins 33 being provided on the upper section to increase the effective heat transfer surface. The resulting mixture of ammonia and hydrogen, that is, gas rich in ammonia, passes from the evaporator coil 14 through conduit 34 which communicates at 45 its lower end with the lower end of an absorber 35 about which is arranged a coil 36 through which a suitable cooling medium, such as water, is circulated.

Ammonia is absorbed out of the rich gas mixture into weak absorption liquid which enters the upper part of the absorber 35 through a vertically extending conduit 37. The hydrogen, which is practically insoluble and weak in ammonia, passes upward from the absorber 35 55

through conduit 31 into the evaporator coil 14, the conduits 31 and 34 being in heat exchange relation so that heat is transferred from the weak gas flowing toward the evaporator coil to the rich gas flowing to absorber 35.

The absorption liquid flowing downward through the absorber 35 in counter-flow to the gas mixture becomes enriched in ammonia by absorption and passes through conduit 39 and outer conduit 40 of a liquid heat exchanger to chamber 16 of the generator. Liberated ammonia vapor and absorption liquid passes upward through the vertical conduit 26 into the upper part of the stand-pipe 18, as explained above, to a higher level than it is in the absorber 35, and absorption liquid weak in ammonia flows from chamber 17 through an inner conduit 42 of the liquid heat exchanger and conduit 37 into the upper end of the absorber 35. A portion of conduit 37 is provided with a plurality of fins 43 to effect additional cooling of the weak absorption liquid entering the absorber 35.

In order to vary the total pressure in the refrigeration system just described with changes in air temperature, a vessel 44' for storing hydrogen is provided having one end thereof communicating through a conduit 45' with the lower end of the condenser 28, and the opposite end thereof communicating through a conduit 46' with the gas circuit. The vessel 44' and conduits 45' and 46' provide a path of flow from the condenser 28 to the gas circuit, so that any hydrogen which passes into the condenser can flow to the gas circuit and not be trapped in the condenser. Further, should the air temperature increase so that ammonia is not liquefied in the condenser, the ammonia vapor will flow through conduit 45' to displace hydrogen in the vessel 44' and force hydrogen through conduit 46' into the gas circuit. This raises the total pressure in the system so that an adequate condensing pressure results for the increased air temperature.

In order to maintain the cooling element 14 substantially at a desired temperature, an expandable fluid thermostat responsive to the temperature of the cooling element is arranged to control valve 23 and regulate the flow of gas to the burner 19. The expandable fluid thermostat contains a volatile fluid and comprises a bulb 44 secured to and in thermal contact with the shell 32 of the cooling element 14, an expandable diaphragm 45 communicating with and secured to a hollow member 46, and a conduit 47 connecting the bulb 44 and hollow member 46. The expandable diaphragm 45 and hollow member 46 are arranged to be supported within casing 47 by a resilient diaphragm 48 to which the hollow member 46 is secured. The expandable diaphragm 45 contacts stem 49 of valve 50 which is urged toward its closed position by a resilient spring 51.

When the cooling element tends to rise above the desired temperature the expandable fluid thermostat causes the expandable diaphragm 45 to expand and move the valve 50 downward against the tension of spring 51 to increase the flow of gas to the burner 19; and conversely, when the cooling element 14 tends to fall below the desired temperature, the expandable fluid thermostat causes the expandable diaphragm 45 to contract and permit the valve 50 to be urged toward its closed position to decrease the flow of gas to the burner 19. An adjustment screw 52 bearing against the resilient diaphragm 48 is provided to regulate the position of the expandable diaphragm 45 and hence maintain the cooling element 14 at

a particular desired temperature. The control valve 23 and expandable fluid thermostat associated therewith, during normal operation of the refrigeration apparatus, maintain the cooling element 14 substantially at a desired temperature. 5

In certain instances it is desirable to modify the normal operation of the refrigeration apparatus, and this is especially true when it is desired to melt frost that has accumulated on the upper section of the cooling element 14 and the shell 32 within which the lower section thereof is arranged.

In accordance with our invention we provide a control device, which is arranged within the storage compartment 12 and generally illustrated at 53, to modify the normal operation of the refrigeration apparatus. The control device includes a thermal element or bulb 54 which forms part of an expandable fluid thermostat for controlling the valve 22, as will be described hereinafter. The bulb 54, referring to Figs. 4 and 5, is partially embedded in a metal sleeve 55 which is rectangular in section and secured, as by welding, to the inner sides of an angle bracket 56. The bracket 56 is secured by capscrews 57 to the bottom of the shell 32 at one edge thereof and thermally insulated therefrom by a strip of insulating material 58 and ferrules 59 on the capscrews which are also formed of insulating material. 30

The bulb 54, which is spaced from and out of thermal contact with the cooling element 14 due to the manner in which it is secured to the latter, is rendered operative to modify the operation of the refrigeration apparatus by means providing a heat conductive path between the bulb 54 and shell 32 when frost, indicated at 60, has accumulated on the latter. This may be effected automatically by so constructing and arranging the control device 53 that the bulb 54 is placed in thermal contact with the shell 32 upon opening the door 13 of the refrigerator cabinet 10. To this end a rod 61 is provided which is movable in its length-wise direction alongside the cooling element through openings in the inwardly bent ends 62 of the bracket 56. The forward end of the rod 61 is provided with an enlarged head 61' and intermediate the ends of the rod a helical spring 63 is disposed between a flanged member 64 fixed to the rod and a second flanged member 65 fixed to the bracket 56. When the door 13 is closed the spring 63 is compressed and the rod 61 is urged or biased forward with the head 61' bearing against the inner liner of the door. Upon opening the door 13 the rod 61, due to the tension of spring 63, is moved forward. 40

A carriage or metal block 66 is slidably mounted on the rod 61 and, with a forward movement of the rod, is also moved forward by a pin 67 which is fixed to the rod at the rear of the carriage. To the carriage 66 is secured a forwardly extending leaf spring 68 the outer end of which is adapted to slide over and bear lightly against the downwardly depending arm or plate 69 of an inverted U-shaped part of the bracket 56. When the door 13 is opened and no frost or only a slight amount of frost has accumulated on the shell 32, the carriage 66 is moved forward by the pin 67 and the curved portion of the leaf spring 68 is spaced from and out of thermal contact with ribbed portion 70 of the shell 32. With such forward movement of the carriage 66 the latter slides over the top surface of the sleeve 55 within which is embedded the bulb 54. To insure good thermal contact between the carriage 66 and sleeve 55, a 75

- curved leaf spring 71 is secured within the inverted U-shaped part of the bracket 56. Upon subsequently closing the door 13, the rod 61 is moved rearwardly and, to effect rearward movement of the carriage 66, a helical spring 72 is provided having one end secured to the carriage and the other end secured to the bent end 62 of the bracket 56. The spring 72 is weaker than spring 63 so that, when the door 13 is opened, forward movement of the rod 61 and carriage 66 is insured. When the carriage 66 is moved forward by the rod 61 and pin 67 upon opening the door 13, and the shell is coated with a layer of frost of considerable thickness, as indicated at 60, the curved portion of leaf spring 68 contacts the frost at the ribbed portion 70 of the shell 32 and the outer end thereof frictionally engages the downwardly depending arm 69. Upon subsequently closing the door 13 the rod 61 is moved rearwardly but the carriage 66, due to the layer of frost 60, remains adjacent the ribbed portion 70 of the shell 32. With the carriage in this position, a heat conductive path between the shell 32 and bulb 54 is provided through the layer of frost 60, leaf spring 68, carriage 66 and sleeve 55 within which the bulb 54 is embedded. Due to this heat conductive path the temperature of the bulb 54 is reduced and reaches a value which is approximately that of the shell 32. When the temperature of the bulb 54 is reduced it is effective to operate valve 22 and reduce the flow of gas to the burner 19, thereby stopping the operation of the refrigeration apparatus and permitting melting of frost on the cooling element. This may be accomplished, as shown in Fig. 1, by connecting the bulb 54 to a conduit 54' which is connected at its lower end to the upper chamber 73 of valve casing 74 within which is arranged a flexible partition or diaphragm 75. The diaphragm 75 contacts the upper end of stem 76 of valve 77 which is urged to its closed position by a resilient spring 78. The bulb 54, conduit 54' and chamber 73 constitute an expansible fluid thermostat containing a volatile fluid which increases and decreases in volume with corresponding changes in temperature. During normal operation of the refrigeration apparatus when the bulb 54 is out of thermal contact with the shell 32, the volatile fluid is effective to flex the diaphragm 75 downward against the tension of spring 78 and maintain the valve 77 in its open position, so that valve 23 alone is operative to control the operation of the refrigeration apparatus in response to the temperature of the cooling element. When a layer of frost has accumulated on the shell 32 and the carriage 66 and spring 68 bridge the gap between the shell 32 and bulb 54 and the temperature of the latter is reduced, the volume of the volatile fluid will be decreased and the spring 78 effective to move the valve to its closed position to reduce the flow of gas to the burner. When the main supply of gas is shut off, a small quantity of gas flows through the by-pass 25 to maintain a pilot flame at the burner 19. After the carriage 66 has once been moved adjacent to the ribbed portion 70 of the shell 32 and the operation of the refrigeration apparatus has been stopped, any closing and opening movements of the door 13 will not affect the defrosting of the refrigeration apparatus. Only after the layer of frost 60 has melted sufficiently to reduce the frictional engagement of the spring 68 with the arm 69 and permit spring 72 to pull the carriage rearwardly will the bulb 54 again be out of thermal contact with the shell 32. With the

carriage 66 in a position to the rear of the ribbed portion 70 of the shell 32, the volatile fluid in the bulb 54, conduit 54' and chamber 73 of valve 22 will be increased in volume and effective to move the valve 77 to its open position, and the refrigeration apparatus will again resume normal operation under the control of valve 23 and bulb 44.

In order to provide an effective heat conductive path when the carriage 66 is maintained in position adjacent the ribbed portion 70 of the shell, due to a layer of frost, the carriage 66 and spring 68 are preferably formed of metal which is a good heat conductor. The carriage 66, for example, may be formed of aluminum, copper or brass, and the leaf spring 68 may be formed of copper, beryllium or steel. If desired, the operation of the control device 53 may be effected manually instead of automatically upon opening the door 13. In some instances it may not be desirable to initiate defrosting, as when immediate freezing of water is desired, and in such cases suitable locking means may be provided which will prevent forward movement of the rod 61 when the door 13 is opened. When the control device 53 is operated manually, such manual operation may be effected from outside the refrigerator cabinet 10 by suitable connecting means. In order to insure frictional engagement of the spring 68 with the arm 69 of bracket 56 when a layer of frost has accumulated on the shell 32, the latter may be provided with projections or teeth which will permit forward movement of the carriage 66 but prevent rearward movement of the carriage when the shell is coated with a layer of frost.

In view of the foregoing it will be understood that we have provided an improved control device for refrigeration apparatus and, while we have shown and described a single embodiment of our invention, such variations and modifications are contemplated as fall within the true spirit and scope of our invention, as pointed out in the following claims.

What is claimed is:

1. A refrigerator comprising a cabinet having a thermally insulated storage compartment provided with an opening, a door for closing the opening, refrigeration apparatus including a cooling element arranged to cool the storage compartment, a thermostat having a part spaced from said cooling element for controlling the operation of said refrigeration apparatus, and structure operable upon opening said door to provide a heat conductive path between said part and frost accumulated on said cooling element to render said thermostat capable of modifying the operation of said refrigeration apparatus to cause melting of the frost.

2. A refrigerator comprising a cabinet having a thermally insulated storage compartment provided with an opening, a door for closing the opening, refrigeration apparatus including a cooling element arranged to cool the storage compartment, a thermostat having a part spaced from said cooling element for controlling the operation of said refrigeration apparatus, and structure operable upon opening said door to provide a heat conductive path between said part and frost accumulated on said cooling element to render said thermostat capable of modifying the operation of said refrigeration apparatus to cause melting of the frost, said structure being so constructed and arranged that the modified operation of said refrigeration apparatus is continued irrespective of subsequent closing and opening.

movements of said door until said cooling element is substantially defrosted.

3. A refrigerator comprising a cabinet having a thermally insulated storage compartment provided with an opening, a door for closing the opening, refrigeration apparatus including a cooling element arranged to cool the storage compartment, a thermostat having a part spaced from said cooling element for controlling the operation of said refrigeration apparatus, and structure operable upon opening said door to provide a heat conductive path between said part and frost accumulated on said cooling element to render said thermostat capable of modifying the operation of said refrigeration apparatus to cause melting of the frost, said structure being so constructed and arranged that the heat conductive path is broken and the modified operation of said refrigeration apparatus is terminated when said cooling element is substantially defrosted.

4. Refrigeration apparatus including a cooling element, a thermostat having a part spaced from said cooling element for controlling said refrigeration apparatus, a metal member arranged to be supported for movement with respect to said cooling element and said part, means for imparting movement to said member to move the latter adjacent to a portion of the cooling element, and structure including said member operative when the latter is positioned adjacent said portion of the cooling element to provide a heat conductive path between said part and frost accumulated on said portion to render said thermostat capable of modifying the operation of said refrigeration apparatus to cause melting of the frost.

5. Refrigeration apparatus including a cooling element, a thermostat having a part spaced from said cooling element for controlling said refrigeration apparatus, a metal member arranged to be supported for movement with respect to said cooling element and said part, means for imparting movement to said member to move the latter adjacent to a portion of the cooling element, structure including said member operative when the latter is positioned adjacent said portion of the cooling element to provide a heat conductive path between said part and frost accumulated on said portion to render said thermostat capable of modifying the operation of said refrigeration apparatus to cause melting of the frost, and means for moving said member away from said portion of the cooling element to open the heat conductive path and terminate the modified operation of said refrigeration apparatus when said cooling element is substantially defrosted.

6. Refrigeration apparatus including a cooling element, a thermostat having a part spaced from said cooling element for controlling said refrigeration apparatus, a rod supported for lengthwise movement alongside said cooling element, a metal member movable on said rod with respect to said part, means on said rod for imparting movement to said member to move the latter adjacent to a portion of said cooling element when movement is imparted to said rod, and structure including said member operative when the latter is positioned adjacent to said portion of the cooling element to provide a heat conductive path between said part and frost accumulated on said portion to render said thermostat capable of modifying the operation of said refrigeration apparatus to cause melting of the frost.

7. Refrigeration apparatus including a cooling element, a thermostat having a part spaced from said cooling element for controlling said refriger-

ation apparatus, a rod supported for lengthwise movement alongside of said cooling element, a metal member movable on said rod with respect to said part, means on said rod for imparting movement to said member to move the latter adjacent to a portion of said cooling element when movement is imparted to said rod, structure including said member operative when the latter is positioned adjacent to said portion of the cooling element to provide a heat conductive path between said part and frost accumulated on said portion to render said thermostat capable of modifying the operation of said refrigeration apparatus to cause melting of the frost, and means for moving said member away from said portion of the cooling element independent of any movement of said rod to open the heat conductive path and terminate the modified operation of said refrigeration apparatus when said cooling element is substantially defrosted.

8. A refrigerator comprising a cabinet having a thermally insulated storage compartment provided with an opening, a door hinged to said cabinet for closing the opening, refrigeration apparatus including a cooling element arranged within the storage compartment, a thermostat having a part arranged adjacent to and spaced from said cooling element for controlling the operation of said refrigeration apparatus, a metal member arranged to be supported for movement toward and away from a portion of said cooling element, means operable upon opening said door for imparting movement to said member to move the latter adjacent to said portion of the cooling element, and structure including said member operative when the latter is positioned adjacent to said portion to provide a heat conductive path between said part and frost accumulated on said portion to render said thermostat capable of modifying the operation of said refrigeration apparatus to cause melting of the frost.

9. A refrigerator comprising a cabinet having a thermally insulated storage compartment provided with an opening, a door hinged to said cabinet for closing the opening, refrigeration apparatus including a cooling element arranged within the storage compartment, a thermostat having a part arranged adjacent to and spaced from said cooling element for controlling the operation of said refrigeration apparatus, a metal member arranged to be supported for movement toward and away from a portion of said cooling element, means operable upon opening said door for imparting movement to said member to move the latter adjacent to said portion of the cooling element, and structure including said member operative when the latter is positioned adjacent to said portion to provide a heat conductive path between said part and frost accumulated on said portion to render said thermostat capable of modifying the operation of said refrigeration apparatus to cause melting of the frost, said structure including resilient means carried by said member and adapted to bear against frost on said portion of the cooling element to maintain said member adjacent to said portion with subsequent closing and opening movements of said door until said cooling element is substantially defrosted.

10. A refrigerator comprising a cabinet having a thermally insulated storage compartment provided with an opening, a door hinged to said cabinet for closing the opening, refrigeration apparatus including a cooling element arranged within the storage compartment, a thermostat having a part arranged adjacent to and spaced from said

- cooling element for controlling the operation of said refrigeration apparatus, a metal member arranged to be supported for movement toward and away from a portion of said cooling element, 5 means operable upon opening said door for imparting movement to said member to move the latter adjacent to said portion of the cooling element, structure including said member operative when the latter is positioned adjacent to said portion 10 to provide a heat conductive path between said part and frost accumulated on said portion to render said thermostat capable of modifying the operation of said refrigeration apparatus to cause melting of the frost, and means for moving said member away from said portion of the cooling element to open the heat conductive path and terminate the modified operation of said refrigeration apparatus when said cooling element is substantially defrosted. 15
11. Refrigeration apparatus including a cooling element, a thermostat having a part adjacent to and spaced from said cooling element for controlling said refrigeration apparatus, a metal member arranged to be supported for movement toward 20 and away from a portion of said cooling element, a plate disposed adjacent to and spaced from said portion of the cooling element, a curved resilient leaf spring carried by said member, means for imparting movement to said member to move the latter adjacent to said plate and said portion of the cooling element, said spring contacting frost on said portion of the cooling element and frictionally engaging said plate when sufficient frost has accumulated on said portion, and structure 25 including said spring and said member operative when the latter is positioned adjacent to said portion of said cooling element to provide a heat conductive path between said part and the frost to render said thermostat capable of modifying 30 the operation of said refrigeration apparatus to cause melting of the frost.
12. Refrigeration apparatus including a cooling element, a thermostat having a part adjacent to and spaced from said cooling element for controlling said refrigeration apparatus, a metal member arranged to be supported for movement toward and away from a portion of said cooling element, a plate disposed adjacent to and spaced from said portion of the cooling element, a curved 35 resilient leaf spring carried by said member, means for imparting movement to said member to move the latter adjacent to said plate and said portion of the cooling element, said spring contacting frost on said portion of the cooling element and frictionally engaging said plate when sufficient frost has accumulated on said portion, structure including said spring and said member operative when the latter is positioned adjacent to said portion of the cooling element to provide a heat conductive path between said part and the frost to render said thermostat capable of modifying 40 the operation of said refrigeration apparatus to cause melting of the frost.
13. Absorption refrigeration apparatus including a generator and a cooling element, a burner for heating said generator, means including a conduit for conducting fuel to said burner, a thermostat having a part thermally spaced from 45 said cooling element for controlling the flow of fuel to said burner, and structure including a metal member movable with respect to said part and operative to provide a heat conductive path between said part and frost accumulated on said cooling element to render said thermostat capable of reducing the flow of fuel to said burner to modify the operation of said refrigeration apparatus and cause melting of the frost. 50
14. Absorption refrigeration apparatus including a generator and a cooling element, a burner for heating said generator, means including a conduit for conducting fuel to said burner, a first thermostat having a part responsive to a temperature condition affected by said cooling element for normally controlling the flow of fuel to said burner to maintain said cooling element substantially at a desired temperature or temperature range, a second thermostat having a part thermally spaced from said cooling element for controlling the flow of fuel to said burner, and structure including a metal member movable with respect to said part and operative to provide a heat conductive path between said part of the second thermostat and frost accumulated on said cooling element to render said second thermostat capable of controlling the flow of fuel normally affected by said first thermostat to modify the operation of said refrigeration apparatus and cause melting of the frost. 55
15. Refrigeration apparatus including a cooling element, a thermostat element spaced from said cooling element for controlling said refrigeration apparatus, said thermostat element being fixed with respect to said cooling element when frost melts on the latter, and a thermal conductive member movable with respect to said thermostat element and operative to bridge the gap between said thermostat element and frost on said cooling element to render said thermostat element capable of modifying the operation of said refrigeration apparatus to cause melting of frost on said cooling element. 60
16. Refrigeration apparatus including a cooling element, a thermostat element thermally spaced from said cooling element, said thermostat element being fixed with respect to said cooling element when frost melts on the latter, a thermal conductive member movable with respect to said thermostat element and adapted to be interposed between said thermostat element and said cooling element, and said thermal conductive member being so constructed and arranged that it is retained in position between said thermostat element and frost on said cooling element when frost has accumulated on the latter to provide a heat conductive path between frost on said cooling element and said thermostat element, whereby said thermostat element is capable of modifying the operation of said refrigeration apparatus to cause melting of frost on said cooling element. 65
17. Refrigeration apparatus including a cooling element, a thermostat element spaced from said cooling element for controlling said refrigeration apparatus, and a thermal conductive member to provide a heat conductive path between said thermostat element and frost on said cooling element to render said thermostat element capable of modifying the operation of said refrigeration apparatus to cause melting of frost on said cooling element, said thermal conductive member being movable with respect to said thermostat element during normal operation of said refrigeration apparatus and when frost tends to accumulate on said cooling element. 70
18. Absorption refrigeration apparatus including a generator and a cooling element, a burner for heating said generator, means including a conduit for conducting fuel to said burner, a thermostat having a part thermally spaced from said cooling element for controlling the flow of fuel to said burner, and structure including a metal member movable with respect to said part and operative to provide a heat conductive path between said part and frost accumulated on said cooling element to render said thermostat capable of reducing the flow of fuel to said burner to modify the operation of said refrigeration apparatus and cause melting of the frost. 75

18. In refrigeration apparatus including a cooling element and having a source of energy supply, and thermostatic means responsive to a temperature condition affected by said cooling element for normally controlling the energy supply, additional thermostatic means including a part spaced from said cooling element, and structure including a metal member movable with respect to said part to provide a heat conductive path between said part and frost accumulated on said cooling element to render said additional thermostatic means capable of controlling the energy supply normally affected by said first-mentioned thermostatic means to modify the operation of

said refrigeration apparatus to cause melting of the frost.

19. Refrigeration apparatus including a cooling element, a thermostat including a part thermally spaced from said cooling element for controlling said refrigeration apparatus, and structure including a thermal conductive member movable with respect to said part and operative to provide a heat conductive path between said part and frost on said cooling element to render said thermostat capable of modifying the operation of said refrigeration apparatus to cause melting of frost on said cooling element.
